SPINNING BOBBIN

Ernst Beck, Bitterfeld, Germany, assignor to I. G.
Farbenindustrie Aktiengesellschaft, Frankfort-
on-the-Main, Germany

Application October 21, 1931, Serial No. 570,211
In Germany December 1, 1930

1 Claim. (Cl. 242—118)

My present invention relates to flanged bobbins. Difficulties arise in unwinding yarn over the top of a flanged bobbin if the shaft and the flange differ much in diameter. The unwinding of the thread is much impeded by the friction at the upper flange of the bobbin, when there are still but a few layers of yarn on the bobbin.

My invention consists in a flanged bobbin, one or both flanges of which comprise one or more detachable rings permitting reduction of the diameter of the upper flange when the thread has been in part drawn off.

Bobbins having flanges detachable as a whole have already been described; the essence of this invention, however, is the composite nature of the flange.

In order to protect the running thread it has also been proposed to fit a lid with a smoothly polished border over the upper flange, before winding off the thread from the flanged bobbin set upright.

A bobbin according to this invention has flanges which consist of rings fitted together. The outer periphery of each ring is polished in order to reduce as much as possible the friction of the thread against the periphery.

An example of such a bobbin is illustrated in the accompanying drawing, in which:

Fig. 1 shows a front view of my new bobbin, partially in section, and Fig. 2 shows a plan view of my new bobbin.

Fig. 1 shows a flanged bobbin, the upper flange of which consists of two parts, the ring *f* having been removed. The spindle *a* has a bore *g*, a lower flange *b*, and an upper flange *c, f*. The detachable ring *f* is attached by a screw thread (as shown in Fig. 1), a bayonet-catch or the like *e* to the flange *c* and is placed on a polished pad *d*. When the yarn has been unwound to such an extent that the ring *f* may be removed, the thread glides against the pad *d*.

The flanges of the bobbin may consist of two or more parts. They may be made from wood, metal, artificial materials or the like. They may also be made from different materials. Thus the shaft and the lower flange may be made, for instance, from wood, and the upper flange, consisting of several parts, may be made from vulcanized fiber or from metal.

What I claim is:—

A flanged bobbin, at least one flange of said bobbin comprising at least two rings having polished outer peripheries and fitted within one another, the outer rings being detachable from the inner ring, for the purpose described.

ERNST BECK.
